BY

UNITED STATES PATENT OFFICE

ERWIN SOHN, OF OAK PARK, ILLINOIS

RACK FOR ELECTROPLATING

Application filed December 30, 1928. Serial No. 157,919.

This invention relates to a rack for use in electroplating. In chromium plating processes it is difficult to secure uniform current distribution, especially when plating irregularly shaped objects. To correct this situation, use is made of what is hereinafter called "booster" current, as will later be explained in connection with the description of the drawings.

It is an object of this invention to provide an improved rack for holding articles during electroplating.

Several modifications of my invention adapted for use in chromium plating are illustrated in the drawings.

As shown on the drawings:

Figure 1 is a top plan view of an electroplating vat, with parts broken away and in section.

Figure 2 is a cross sectional view of the same.

Figure 3 is a fragmentary elevational view of a cathode rack.

Figure 4 is an enlarged sectional view taken substantially on line IV-IV of Figure 2, and illustrating the method of suspending articles to be plated.

Figure 5 is an enlarged sectional detail view.

Figure 6 is an elevational view of a modified form of cathode rack.

Figure 7 is an end view of the same.

Figure 8 is an enlarged fragmentary view illustrating a method of suspending an article to be plated.

Figure 9 is an enlarged detail sectional view.

Figure 10 is an elevational view of a second modified form of rack.

Figure 11 is a sectional view taken on line XI-XI of Figure 10.

Figure 12 is an enlarged detail sectional view, and

Figure 13 is a sectional view taken on line XIII-XIII of Figure 10.

As illustrated in Figures 1 and 2, the reference numeral 1 indicates a typical rectangular shaped vat for carrying out the electrodeposition of chromium. Anode plates 2, preferably of ferrous metal, are adapted to

be suspended in said vat 1 by means of their hooked ends 3 from anode bus bars 4. There are preferably two sets of anode plates positioned lengthwise of the vat and adjacent the side walls thereof. A cathode rack or series of racks 5 is suspended between said anode plates 2 from a cathode bus bar 6. Each of said cathode racks 5 comprises a bar 7 having a hooked upper end 8 adapted to be engaged over the bus bar 6. Said bar 7 is provided at spaced intervals with a plurality of spring clip members 9 on which articles 10 are adapted to be suspended in the plating bath. Said clip members 9 comprise flat strips of springy metal secured intermediate their ends to the rod 7 and arranged on opposite sides thereof. The ends of each set of said clips 9 diverge as at 11 for the purpose of securely engaging within hollow articles, such as 10, which are to be plated. Said article 10 represents a hollow cap having a threaded recess 16 and perforations 50 in the top thereof.

Ordinarily it is very difficult if not impossible to plate the surface of a perforated article or the inside of hollow articles with an even and uniform plating or coating. I have found however that if the current strength is locally increased or boosted in the locality of the recess or hollow portion that the plating may be very satisfactorily effected. In this connection, a small rod 12 of ferrous metal is inserted in the bar 7 and insulated therefrom by means of mica bushings 13 and washers 14 and secured to said bar 7 by means of nuts 15. One of said bars 12 is positioned between adjacent members of each set of clips 9 and extends on each side of the bar 7 so as to project a short distance into the recess 16, in the article 10. Lead wires 17 connect each of the rods 12 with one or the other of the anode bus bars 4, to which said lead wires are secured by means of bands or clips 18. In this way, the anode current is conducted to a point adjacent the recess 16 so as to boost the current strength locally at that point. As a result the inner surface of hollow articles may be readily plated. Also the current strength is sufficiently increased by this means in the locality of the perfora-

tions 50 to cause the surface to be plated to the very edges of said perforations.

It will be understood that the articles to be plated are in electrical contact through the 5 clips 9 and the bar 7 with the cathode bus bar, and that said articles form a part of the cathode. In order to prevent excessive loss of current from the surface of the bar 7 and clips 9, these surfaces are preferably coated 10 with an insulating compound of asphaltic nature or covered with a molten asphaltic base compound.

In Figures 6 to 9 inclusive there is shown a modified form of cathode rack 20 suspended 15 from a cathode bus bar 21. Said rack 20 comprises a pair of vertical end strips 22 joined by means of spaced parallel horizontal bars 23. At spaced intervals along said bars 23 are secured pegs 24 on which articles 20 25 are adapted to be suspended for plating. As shown, the article 25 is a bib or portion of a faucet having a threaded end 26 into which the peg 24 may be inserted. On account of the fillets such as 27 in an article of this type, 25 it is very difficult to secure an even and uniform coating. Accordingly, booster current is supplied by means of a plurality of wires 28 of ferrous metal of suitable size and suitably spaced, carrying anode current. Said 30 wires 28 are suspended between pivotal arms 29 carried by the end strips 22 but insulated therefrom by insulation 32 and 33. Each of said arms 29 is provided with a plurality of closely spaced holes 30, through which the 35 wires 28 may be passed. Lead wires 31 connect said arms 29 to the anode bus bar (not shown). It will be understood that the number of booster current wires 28 used and their relative position to the article to be plated 40 may be varied to suit the particular conditions.

Where there is a large opening in the article to be plated, such as the opening 51 in the article 25, and it is desired to plate to the 45 edge of the opening, it is necessary to plug the opening, as by means of a lead plug.

In Figures 10 to 13 inclusive there is shown a second modified form of rack 34 adapted for use in plating certain types of 50 articles, such as illustrated by the reference numeral 35. In this case the articles 35 are secured to the vertical strips 36 of the rack 34 and spaced thereupon by means of split pegs 37 extending into holes 38 in said articles 35. Each of said articles 35, as shown, comprises a curved flat strip having lugs 39 extending from one face thereof. It is preferable to stagger the articles 35 by spacing them vertically and placing them on alternate 55 opposite sides of the strips 36 with the lugs 39 extending inwardly. It is then possible by means of booster current wires 40 positioned at suitable points with respect to the lugs 39 to obtain an even and uniform plating 60 of chromium on both the body portion

of the articles 35 and on the fillet surfaces of the lugs 39. Said wires 40 are suitably suspended from cross bars 41 secured to the strips 36 and insulated therefrom by insulation 53. The ends of said wires 40 may be 70 threaded and provided with nuts 42, both the wire and nuts being in electrical contact with the cross bar 41. Lead wires 44 connect said cross bar 41 to the anode current.

It is obvious that the type of apparatus 75 used will vary with the nature of the work to be plated, but the various types shown in the drawings will serve to illustrate the principle by which the surface of hollow or perforated articles and articles having irregular 80 contours may be successfully chromium plated.

I am aware that many changes may be made and numerous details of the process and construction may be varied through a wide 85 range without departing from the principles of this invention, and I therefore do not pur- pose limiting the patent granted hereon, otherwise than necessitated by the prior art.

I claim as my invention:

1. As a new article of manufacture, a 90 rack for use in plating articles comprising a bar, resilient means secured at intervals thereto and adapted to be inserted into the articles to be plated to maintain said articles 95 thereon, auxiliary anodes in said bar adapted to project into the articles to be plated, means for insulating the anodes from said resilient means and means for partially insulating said anodes from an electroplating solution.

2. As a new article of manufacture, a rack 100 for use in plating irregular articles comprising a bar, a plurality of spring strips mounted at intervals on said bar and adapted to project into the articles to be plated to maintain said articles thereon, anodes adjustably mounted in said bar adjacent said spring strips whereby they may be properly positioned with respect to the articles so as 105 to control the current density acting on said articles, means for insulating said spring strips from said anodes, and means for connecting said spring strips to a negative current lead and said anodes to a positive lead.

3. As a new article of manufacture, a rack 110 for use in plating irregular objects comprising a bar, bowed spring strips secured at intervals to opposite faces of the bar, the strips on one face opposing the strips on the opposite face to form pairs, each pair of 115 strips being adapted to resiliently support an article on an end thereof, an anode arranged in said bar between the springs of each pair of strips with an end thereof adjacent the article on said strips, means for insulating said anodes from said spring strips, and means for connecting the spring strips as cathodes.

4. A device as in claim 3 wherein the spring strips and anodes are secured to the bar adja- 120

130

cent the midpoints of the same whereby an article may be supported and plated on both ends of the spring strips.

5. Apparatus for plating irregular shaped articles with metals from solutions of low throwing power comprising a plating tank, anodes therein, a plating rack adjacent said anodes, said rack comprising a bar supported at its end in said tank, spring strips in 10 pairs secured to said bar, each pair being constructed to resiliently maintain an article on an end thereof, an anode situated in said bar between the members of each pair of springs with an end thereof positioned in proximity 15 to the irregular surface of an article, means for insulating said anodes from said springs, and means for electrically connecting said springs as cathodes and said second anodes to a positive source of current.
- 20 6. A device as in claim 2 wherein each pair of springs and each anode are secured to the rack bar adjacent their respective midpoints whereby an article may be supported and plated on both ends of a pair of springs.
- 25 In testimony whereof I have hereunto subscribed my name.

ERWIN SOHN.
